(57) CLAIM

The ornamental design for a load brace, as shown and described.

DESCRIPTION

FIG. 1 is a perspective view of a load brace showing my new design.

FIG. 2 is a side view thereof;

FIG. 3 is an opposite view thereof;

FIG. 4 is a rear view thereof;

FIG. 5 is a front view thereof;

FIG. 6 is a top view thereof; and,

FIG. 7 is a bottom view thereof.

The broken lines shown the drawings are for the purposes of illustrating environmental structure which form no part of the claimed design.
